UNITED STATES PATENT OFFICE.

KARL THOMANN, OF HALLE, GERMANY.

ROTARY ENGINE.

SPECIFICATION forming part of Letters Patent No. 645,437, dated March 13, 1900.

Application filed November 9, 1898. Serial No. 695,980. (No model.)

To all whom it may concern:

Be it known that I, KARL THOMANN, a subject of the Emperor of Germany, and a resident of Halle, in the Empire of Germany, have 5 invented certain new and useful Improvements in Rotary Engines, of which the following is a specification.

This invention has for its object an improved rotary motor for steam, gas, or compressed air. The annular working chambers of the same are divided in the ordinary manner into sickle-shaped compartments by means of annular rings located on a rotary plain disk and the said compartments again 15 divided, by means of the slides or pistons arranged in the rings, into admission, expansion, and discharge chambers.

This improved motor is characterized, first, by the working chambers lying on both sides 20 of the plain disk being mutually diametrically displaced—that is to say, lying eccentric to one another; second, by the slides or pistons through which the sickle-shaped chambers are divided oscillating in the rings of 25 the plain disk and by the rings traveling on the inner cores of the casing being guided; third, by the central position of the shaft being secured by means of a special form of the stuffing-box; fourth, by the charge of the motor 30 being adjustable; fifth, by the slide-surfaces lying eccentrically to one another being capable of being mutually adjusted so that the motor always remains tight; sixth, by the parts which work one in the other being adjustable by reason of their conical shape, and thereby allowing of an exact tight fitting of 35 the same; seventh, by the casing being rendered perfectly tight to the outside by means of an adjustable ring.

40 My improved apparatus is shown in the accompanying drawings, in which—

Figure 1 is a vertical diametrical section of this improved motor with tapering or conical inner cores or surfaces. Fig. 2 is a vertical 45 cross-section on the line II II of Fig. 1. Fig. 3 is a similar view to Fig. 2 of the internal appearance of the casing, while Fig. 4 is a sectional view of the plain disk on the line IV IV of Fig. 5 and showing the position of the 50 feed-passages formed in the plain disk of the slides or pistons. Fig. 5 is a vertical diametrical section of the plain disk. Figs. 6, 7, and

8 are separate views of the slides arranged at each side of the plain disk with their conical guide-rings. Fig. 9 is a vertical diametrical 55 section of a similar motor with cylindrical inner surfaces. Fig. 10 is a vertical cross-section of the motor shown in Fig. 9 on the line IX IX. Fig. 11 is a detail view.

The constructive arrangement of the motor 60 is as follows: The two parts 1 and 2 of the casing each has internally an eccentric core 3, projecting toward the inside, so that as usual an annular chamber results. Both halves of the casing are, however, mutually 65 displaced diametrically in such a way that they stand eccentrically vertically to one another, and the driving-shaft 4, mounted in the inner core 3, is also eccentrically mounted in the said chambers. A plain disk 5 is 70 mounted on the driving-shaft 4 and carries on each side an annular ring 6, mounted concentric to the driving-shaft. On each internal core a number of slide-rings 7 are arranged, the number of which agrees with the 75 number of slides or pistons 8, situated on each side of the plain disk. In the present case three such slides 8 are employed, which are adapted to move radially and to oscillate on each side of the plain disk in the annular 80 working chambers, and corresponding therewith there are on each inner core 3 three rings 7, each of which is connected with one of the slides 8. In each annular ring 6 bolts 9, which are slotted, but which are revoluble, 85 are mounted, and each of them carries a slide 8. As each annular ring encounters with its outer surface at the point α the inner wall of its part of the casing and at the point β the outer surface of its slide-ring 7 the 90 annular working chamber is divided into sickle-shaped compartments, as may be seen in Figs. 2 and 10. As, therefore, each inner core 3, on which the slide-rings 7 with the 95 slides 8 rotate, lies eccentrically to the driving-shaft 4, and therefore to the axis of rotation of the plain disk 5, the slides 8 execute not merely a reciprocating movement in the bolts 9, but also an oscillating one, and for this object the bolts 9 are provided, so that 100 the slides are always guided in a tight slot and yet can oscillate. Also in order that the slides in any position of the plain disk 5 may lie in the radius of the inner core they are, as

already mentioned, guided by means of the rings 7.

The slides 8 divide each sickle-shaped chamber in the indicated number into an admission-chamber *a*, expansion-chamber *e*, and discharge-chamber *v*. (See Figs. 2 and 10.) The medium of pressure acts first in the inner sickle-shaped chamber III, passes through the transfer-passage 10 into an outer sickle-shaped chamber V, and there acts again in order to finally escape through the discharge-passage 11 to the exit. This action takes place on both sides of the plain disk 5 at different places, but in the same direction, so that the driving-shaft 4 does not experience a strain on one side.

In order to be able to work with a variable charge, the steam-admission passage 12 opens into a segment-shaped recess 13 on the inner side of the inner core 3, in which recess a segment-shaped slide 14 is arranged. The latter is mounted on a shaft 15 and may be regulated from the outside by means of a setting-lever 16. The plain disk 5 has on each plane surface so-called "feed-passages" 17, which are shown in Fig. 4 on the plane surfaces and also in Fig. 5. As may be seen from this latter figure, the feed-passages 17 have a special form. When by the rotation of the plain disk 5 they reach the dotted position *d*, they are closed against the passage 12 and the charge is finished. If the slides 14 be moved in the direction of the hands of a watch farther to the right, the charge is increased, because the part of the segment-shaped recess 13 corresponding with the passage 12 connects longer with the feed-passage. If two of the slides 8 in the sickle-shaped chamber III or V assume a symmetrical position to the vertical in the indicated position of the motor, the chamber contained between them must be regarded as a maximum expansion-chamber and the expansion reaches its end. From this position onward the discharge must take place, and for this object a transfer-passage 10, provided with a trough-shaped recess *r*, arranged in the casing, is provided, which recess expands or enlarges up to the position *x*, so that on the further movement of the slide a discharge may take place from the said wedge-shaped expanding-chamber. In order, however, that the charge or feed may take place after the transfer of the medium of power from the sickle-shaped chamber III to V has taken place already in the indicated position of Fig. 2, the transmission-passage in this chamber is also provided with a trough-shaped extension *s*, Figs. 2, 3, and 10. A discharge-passage 11, through which the consumed medium of power escapes, is also provided with a similar trough-shaped passage *n*. If the cylinder-surfaces which travel one on the other become worn at the points *x* and *y*, they may again be rendered tight in case the motor is given a conical form, as is shown in Fig. 1, by screwing together the two casings. As the exact coincidence of the sur-

faces engaging with one another causes very much work, the inner wall of the casing and the slide-ring 7 may be made adjustable 70 against the annular ring 6 of the plain disk 5, as is shown in the cylindrical form of construction represented in Figs. 9 and 11. For this object a separate plain ring 19 is inserted in the interior of the casing, which forms 75 the inner wall of the casing and may be exactly adjusted by means of screws 20. The readjustment may, however, be effected also by means of an eccentric shaft 21, (see Fig. 11,) arranged in the casing or in any other 80 suitable manner. The slide-ring 7 may, as shown in Fig. 10, also be adjusted by means of an eccentric shaft 22, mounted in the inner core 3, so that they again always travel quite tightly against the annular ring 6 of 85 the plain disk.

In order to render the interior of the casing quite tight to the outside, a ring 23 is screwed into the one casing half, which ring engages in a groove of the other half-casing. In this 90 groove washering material is placed which is compressed by means of the ring 23. The whole casing of the motor may in addition be provided with a covering-casing 26, Fig. 1, and also it may be heated by the discharge- 95 steam or by fresh steam from the boiler.

In order to effect the centering of the driving-shaft 4, it is at both sides of the plain disk 5 formed conically at the places *h*, as shown as an example in Fig. 1, and surrounded by a 100 bush-bearing *i*, which suits itself to the partial conicity *h* of the shaft. The bush-bearing is screwed into the internal core 3 and fixed by means of a safety-nut 24. A stuffing-box 25 of any suitable form of construction 105 may also be arranged on the outer end of the bush-bearing, so that the motor is rendered entirely tight to the outside.

The working of this new motor is as follows: The power medium enters on both sides 110 of the plain disk through the feed-passages 12 and through feed-passages 17, situated in the plain disk, into the inner sickle-shaped chamber III in front of the slide 8 lying nearest thereto—that is to say, in Fig. 4 in 115 front of the upper side—and acts with its entire pressure up to the feed-passage, while the rotation of the plain disk is closed through the slide 14. From this point the expansion takes place up to the maximum expansion 120 admissible in the chamber until the medium of power has thus filled out the chamber *e* in Fig. 2 and then passes through the trough-passage *r*, overflow-passage 10, and through the trough-passage *s* into the sickle-shaped 125 chamber *v* in front of the next slide in order there to act again in the same manner. When it has acted there, it is finally discharged through the passage 11, and this action takes place on both sides of the plain 130 disk—that is to say, in each half of the casing.

If such a motor be operated by steam, it may also work by condensation; but the mo-

tor remains a compound motor immaterially whether the driving be effected by means of steam, gas, or compressed air.

Having thus described my invention, the following is what I claim as new therein and desire to secure by Letters Patent:

1. A rotary motor comprising a driving-shaft, a casing having a feed-passage, a discharge-passage, a core formed with an extension to the feed-passage and with a segmental recess at its inner end with which the extension communicates and located eccentrically on the driving-shaft and an annular chamber located eccentrically to the driving-shaft, the shaft extending through the core provided with a segmental slide located in the segmental recess, a rotary disk having feed-passages in its face, and an annular ring located concentrically to the driving-shaft, and dividing the annular chamber into sickle-shaped working chambers located within and without the annular ring, the slides working radially through the annular ring and the slide-rings loosely mounted on the core; each slide-ring being connected with a slide; substantially as described. 70
2. A rotary motor comprising a driving-shaft, a casing having feed-passages, discharge-passages, cores each formed with an extension to the feed-passage, and with a segmental recess at its inner end with which the extension communicates, and located eccentrically on the driving-shaft and to each other and annular chambers located eccentrically to the driving-shaft and to each other, the shafts extending through the cores each provided with a segmental slide located in the segmental recess, a rotary disk having feed-passages on its faces, and annular rings located concentrically to the driving-shaft and dividing the annular chambers into sickle-shaped working chambers located within and without the annular rings, the slides working radially through the annular rings and the slide-rings loosely mounted on the cores; each slide-ring being connected with a slide; substantially as described. 75
3. A rotary motor comprising a driving-shaft, a casing, a feed-passage, a trough-shaped passage, a transfer-passage, a transmission-passage, a discharge-passage, a core formed with an extension to the feed-passage therethrough, and located eccentrically on the driving-shaft, and an annular chamber located eccentrically to the driving-shaft, a rotary disk having feed-passages in its face, and an annular ring located concentrically to the driving-shaft, and dividing the annular chamber into sickle-shaped working chambers located within and without the annular ring, the slides working radially through the annular ring, and the slide-rings loosely mounted on the core; each slide-ring being connected with a slide; substantially as described. 80
4. A rotary motor comprising a driving-shaft, a casing, a feed-passage, a trough-shaped passage, a transfer-passage, a trough-shaped
- transmission-passage, a discharge-passage, a core formed with an extension of the feed-passage therethrough and with a segmental outlet-recess, and located eccentrically on the driving-shaft, and an annular chamber located eccentrically to the driving-shaft, a rotary disk having feed-passages in its face, and an annular ring located concentrically to the driving-shaft and dividing the annular chamber into sickle-shaped working chambers located within and without the annular rings, the slides working radially through the annular ring, the slide-rings loosely mounted on the core, each slide-ring being connected with a slide, the shaft extending through the core, having, at its inner end a segment-slide located in the segmental recess, and at its outer end a setting-lever; substantially as described. 85
5. A rotary motor comprising a driving-shaft, a casing having a feed-passage, a discharge-passage, a core located eccentrically on the driving-shaft, and an annular chamber located eccentrically to the driving-shaft, a rotary disk having feed-passages in its face and an annular ring located concentrically to the driving-shaft, and dividing the annular chamber into sickle-shaped working chambers located within and without the annular ring, the oscillating bolts having slots and mounted in the annular ring, the slides working through the slots in the oscillating bolts and through the annular ring, and the slide-rings loosely mounted on the core; each slide-ring being connected with a slide; substantially as described. 90
6. A rotary motor comprising a driving-shaft, a casing having two parts adjustable toward each other on the driving-shaft, and having feed-passages, discharge-passages, cone-shaped cores located eccentrically on the driving-shaft and to each other, and annular chambers, cone-shaped in radial section and located eccentrically to the driving-shaft and to each other, a rotary disk having feed-passages on its faces and annular rings cone-shaped in radial section and located concentrically to the driving-shaft and dividing the annular chambers into sickle-shaped working chambers located within and without the annular rings, the slides working radially through the annular rings, the cone-shaped slide-rings loosely mounted on the cores; each slide-ring being connected with a slide, and a packing-ring fitting in the annular grooves of the two parts of the casing; substantially as described. 95
7. A rotary motor comprising a driving-shaft having conical projections, the bearing-bushes adjustable on the conical projections, a casing having feed-passages, discharge-passages, cores located eccentrically on the driving-shaft and to each other, and annular chambers located eccentrically to the driving-shaft and to each other, a rotary disk having feed-passages on its faces and annular rings located concentrically to the driving-shaft 100
- 115
- 120
- 125
- 130

- and dividing the annular chambers into sickle-shaped working chambers located within and without the annular rings, the slides working radially through the annular rings and the slide-rings loosely mounted on the cores; each slide-ring being connected with a slide; substantially as described.
8. A rotary motor comprising a driving-shaft, a casing formed in two parts mutually displaced diametrically in such a way that they stand eccentrically vertically to one another, each part having a feed-passage, a discharge-passage, a core provided with an eccentric extension to the feed-passage and located eccentrically on the driving-shaft, and an annular chamber located eccentrically to the driving-shaft, a rotary disk having feed-passages in its faces and annular rings located concentrically to the driving-shaft, and dividing the annular chambers into sickle-shaped working chambers located within and without the annular rings, and the slides working through the annular rings and each having a slide-ring loosely mounted on its core; substantially as described.
9. A rotary motor comprising a driving-shaft, a casing formed in two parts mutually displaced diametrically in such a way that they stand eccentrically vertically to one another, each part having a feed-passage, a discharge-passage, a core provided with an eccentric extension to the feed-passage and located eccentrically on the driving-shaft, and an annular chamber located eccentrically to the driving-shaft, plain rings providing an inner wall to each annular chamber, means for adjusting the plain rings, a rotary disk having feed-passages in its faces and annular rings located concentrically to the driving-shaft, and dividing the annular chambers into sickle-shaped working chambers located within and without the annular rings, and the slides working through the annular rings and each having a slide-ring loosely mounted on its core; substantially as described.
10. A rotary motor comprising a driving-shaft, a casing formed in two parts mutually displaced diametrically in such a way that they stand eccentrically vertically to one another, each part having a feed-passage, a discharge-passage, a core provided with an eccentric extension to the feed-passage and located eccentrically on the driving-shaft, and an annular chamber located eccentrically to the driving-shaft, a rotary disk having feed-passages in its faces and annular rings located concentrically to the driving-shaft, and dividing the annular chamber into sickle-shaped working chambers located within and without the annular rings, means for adjusting the annular rings radially, and the slides working through the annular rings, and each having a slide-ring loosely mounted on its core; substantially as described.

in and without the annular rings, and the slides working through the annular rings, and each having a slide-ring loosely mounted on its core; substantially as described.

45

10. A rotary motor comprising a driving-shaft, a casing formed in two parts mutually displaced diametrically in such a way that they stand eccentrically vertically to one another, each part having a feed-passage, a discharge-passage, a core provided with an eccentric extension to the feed-passage and located eccentrically on the driving-shaft, and an annular chamber located eccentrically to the driving-shaft, a rotary disk having feed-passages in its faces and annular rings located concentrically to the driving-shaft, and dividing the annular chamber into sickle-shaped working chambers located within and without the annular rings, means for adjusting the annular rings radially, and the slides working through the annular rings, and each having a slide-ring loosely mounted on its core; substantially as described.

50

11. A rotary motor comprising a driving-shaft, a casing having a feed-passage, a discharge-passage, a core formed with an extension to the feed-passage and with a segmental recess at its inner end with which the extension communicates and an annular chamber, the shaft extending through the core provided with a segmental slide located in the segmental recess, a rotary disk having feed-passages in its face, and an annular ring, and the slides working radially through the annular ring; substantially as described.
